UNITED STATES PATENT OFFICE.

JOSEPH R. LANCASTER, OF MORRISANIA, ASSIGNOR TO J. L. MOTT, OF MOTT HAVEN, NEW YORK.

DESIGN FOR WASH-STAND.

Specification forming part of Design No. 6,319, dated December 17, 1872.

To all whom it may concern:

Be it known that I, JOSEPH R. LANCASTER, of Morrisania, in the county of Westchester and State of New York, have invented a new and original Design for Wash-Stands, of which the following is a specification:

The nature of my design is fully represented in the accompanying drawing, to which reference is made.

A represents the base of the stand; B, the standard; C, the bowl; and D, a border above the bowl, each being wrought in ornamental figures upon the surface, forming separate and special designs, as represented in the drawing.

I claim as my invention—

1. The design for the base of a wash-stand, substantially as shown at A in the drawing.
2. The design for the standard of a wash-stand, substantially as shown at B in the drawing.
3. The design for the bowl of a wash-stand, substantially as shown at C in the drawing.
4. The design for the border of the bowl of a wash-stand, substantially as shown at D in the drawing.
5. The combination of the designs represented at A, B, C, and D, in a wash-stand, substantially as specified.

Witnesses: J. R. LANCASTER.
